Joseph H. Pope
By his Attorney
Nelson M. Howard

UNITED STATES PATENT OFFICE.

JOSEPH H. POPE, OF SOUTH HAMILTON, MASSACHUSETTS, ASSIGNOR TO UNITED SHOE MACHINERY CORPORATION, OF PATERSON, NEW JERSEY, A CORPORATION OF NEW JERSEY.

NAILING DIE.

Application filed March 26, 1923. Serial No. 627,766.

To all whom it may concern:

Be it known that I, JOSEPH H. POPE, a citizen of the United States, residing at South Hamilton, in the county of Essex and State of Massachusetts, have invented certain Improvements in Nailing Dies, of which the following description, in connection with the accompanying drawings, is a specification, like reference characters on the drawings indicating like parts in the several figures.

This invention relates to nailing dies and has for its object the improvement of such dies with a view to increasing their usefulness by making a single die capable of operating upon a wide variety of work.

In the accomplishment of the above stated object the invention provides a nailing die constructed and arranged to accommodate itself to work having different characteristics such, for example, as the requirement that nails be driven at certain locations, which may be somewhat different in different individual pieces of work, in combination with features which facilitate quick changing of the die to accommodate substantial changes in the work such, for example, as in changing from the nailing of one size shoe to another.

One useful application of the invention is in a nailing die for heeling machines intended to be used in attaching rubber heels by nails driven from the outside of the shoe, and the illustrative embodiment of the invention which is hereinafter described in detail is such a heeling machine die. It should be understood, however, that the invention is adaptable to other operations than attaching rubber heels and that the specific construction herein disclosed is shown for illustrative purposes only.

My copending application, Serial No. 612,254, filed Jan. 12, 1923, discloses a mechanism which has been used successfully for rubber heel attaching and which has proved to be greatly superior to the nailing dies heretofore used for that purpose. The present invention may, in a certain sense, be regarded as an improvement upon and development of the invention disclosed in the said application.

In my prior invention a plurality of freely movable nail guiding tubes were employed, in connection with a series of inter-changeable pattern plates which provided

for adjustment of the tubes to different nailing patterns. A corresponding series of ring-like heel holders were also provided and these were interchanged to accommodate work of different sizes, at the same time that the nailing pattern plates were interchanged. By the present invention the necessity for interchanging elements of such a mechanism when changing, for example, from one size heel to another, is eliminated, and a self-contained mechanism is provided which requires only a single, simple manipulative adjustment to accommodate it to any of the various requirements of an ordinary run of work.

More specifically a construction is provided whereby manipulation of a single knob changes both the pattern of the nailing and the size of the work holder, to suit the work at hand.

Further features and advantages of the invention will be understood and appreciated from reading the following detailed description of one satisfactory, practical embodiment thereof in connection with the accompanying drawings, in which

Fig. 1 is a plan view of a heeling machine nailing die embodying the invention;

Fig. 2 is a front elevation of the die;

Fig. 3 is a vertical section on the line 3—3 of Fig. 1; and

Fig. 4 is a perspective view showing the parts disassembled but in their proper superposed relation.

Referring now to the drawings, 10 indicates a die block having projecting tongues 12 at its sides and so constructed that it may be readily inserted in the guides provided for that purpose in a well known type of commercial heeling machine such, for example, as that disclosed in my prior Patent No. 1,431,980, dated October 17, 1922, to which reference may be had for a more complete disclosure of the heeling machine itself.

The die block 10 is chambered to provide openings 14 extending entirely through it. The upper end of each of the openings 14 is shaped to form a hemispherical seat for the spherical upper end 18 of one of the nail guiding tubes 20. The pattern of the seat cavities 16 is approximately an average of the patterns of the nailings to be produced by the die.

The upper face of the die 10 is recessed,

as shown at 22, to provide a seat for a retaining plate 24, which is secured to the die by screws 26. The under side of the plate 24 is provided with hemispherical recesses corresponding to the recesses 16, the whole constituting, in effect, a universal joint mounting for the tubes 20. The plate 24 is further perforated with countersunk holes 28 in alinement with the nail and driver guiding tube mountings, providing for the entrance of the nails and drivers into the tubes.

The spherical heads 18 of the tubes have a sufficiently loose fit in their seats to permit the lower, or nozzle, ends of the tubes to move freely in any horizontal direction. By locating the plane of separation between the die 10 and the retaining plate 24 in the diametrical plane of the spheres 18 the manufacture and assembly of the device are made simple and the replacement of a broken or worn out guide tube 20 is made easy. The nozzle ends of the tubes 20 are tapered, as shown at 30, in order that the tubes shall enter and position themselves properly in the nail locating cavities which are commonly formed in the tread face of a rubber heel.

For the purpose of locating the nozzle ends of the tubes 20 in approximately the pattern of the desired nailing a plurality of relatively movable, slotted positioning devices are provided. A stationary plate 32, which is secured to the under side of the die 10 by screws 34, has formed in it a series of slots 36, 38, 40 which are arranged approximately radially with respect to the pattern of the nailing to be produced. The plate 32 is recessed at 42 to receive a slotted guide plate 44, which is movable forwardly and rearwardly of the die, and a slotted slide 46, which is movable transversely of the die. The under side of the guide plate 44 is recessed at the rear, as shown at 48, to permit the slide 46 to move freely beneath the guide plate.

Inasmuch as the guide tubes 20 at the center of the breast and rear of the nailing pattern only require adjustment in a straight line forwardly and rearwardly, the guide plate 44 has a hole 50 which co-operates with the guide tube at the center of the breast, moving it forwardly or rearwardly in the stationary slot 36 when the guide plate is correspondingly adjusted. Inasmuch as the guide tube at the center of the pattern at the rear must be adjusted in the opposite direction from that just described, a slot 52, corresponding in arrangement to the slot 38, is provided in the rear portion of the guide plate 44. The forward or rearward movement of the plate 44, therefore, has no effect upon the rear guide tube, adjustment of the latter being provided for by a diagonal slot 54 in the slide 46, which

is moved in a direction at right angles to the movement of the guide plate 44 by mechanism which will presently be described. Slots 56 in the guide plate 44 are disposed in such angular relation to the stationary slots 40 that the movement of the plate 44 will simultaneously effect the proper adjustment of the remaining guide tubes 20, each of which is surrounded by a coiled spring 58 which serves to maintain the tubes in approximately central relation to the space defined by the co-operating openings in the members 32, 44, 46, but permits the tube to yield sufficiently to accommodate itself to the smaller variations or inaccuracies of the particular piece of work being operated upon.

For the purpose of producing the required movements of the guide plate 44 and the slide 46 in proper relation to each other an actuating cam disk 60 is provided. A circular recess 62 is formed in the under face of the die 10 to receive the cam disk and permit it to be rotated without bodily displacement. In the disk 60 are formed cam slots 64 and 66 which co-operate respectively with cam rolls 68, and 70 upon the guide plate 44 and the slide 46 to produce simultaneously the required movements of the said plate and slide in directions at right angles to each other when the disk 60 is rotated.

Teeth 69 are formed in a portion of the periphery of the cam disk 60, as shown in Figs. 1 and 4, and an adjusting screw 71, having its threads in engagement with the said teeth, is mounted in suitable bearings formed partly in the die member 10 and partly in the member 32 which is secured thereto. An adjusting knob or handle 72, secured to the screw 71, facilitates manipulation of the screw to produce the desired rotative movement of the cam disk, and a pointer 74 secured to the cam disk co-operates with a stationary, graduated scale 76 to indicate the state of adjustment.

Secured to the under side of the plate 32, by means of screws 78, is a heel holder comprising a frame 80 in which are slidably mounted a rear gage fork 82 and two breast corner gage forks 84. The rear gage fork carries a cam roll 86 which engages in a slot 88 formed in the cam disk 60 and each of the forks 84 carries a cam roll 90 which engages in a slot 92 formed in the said disk. It will be apparent that, as the cam disk is rotated to vary the pattern formed by the nozzle ends of the tubes 20, the setting of the gage forks 82, 84 will simultaneously be correspondingly varied to regulate the heel holder to the size of the heel for which the nailing, as arranged, is appropriate.

The range of variation provided for in the illustrated die is sufficient to cover the

range of sizes which commonly have to be dealt with in an ordinary run of work on the heeling machine. When, however, a change is being made from one class of work to another as, for example, when a different number of nails are to be used the die, being self-contained, may be easily and quickly exchanged for another which is suitable for the new kind of work to be operated upon.

Having described the invention, what is claimed as new and desired to be secured by Letters Patent is:

1. A nailing die having a plurality of nail guiding tubes supported to permit free pivotal movement of their nozzle ends, and controlling means arranged to engage said nozzle ends and variably control the pattern of the nailing.
2. In a nailing die the combination of a plurality of nail guiding tubes supported to permit free pivotal movement about points remote from their nozzle ends, and manipulative means constructed and arranged to effect said pivotal movement of the tubes simultaneously.
3. In a nailing die, the combination of a plurality of nail guides, a work gage, and a controller constructed and arranged to change simultaneously the relative positions of the guides and the relative positions of the guides and the gage.
4. In a nailing die, the combination of a

plurality of movable nail guides, a work gage, and a cam device constructed and arranged to change the spacing between the guides and to adjust the gage relatively to the guides.

5. A nailig die comprising a selflocating nail and driver guide having a nozzle shaped to co-operate with the formation of the work at a predetermined point, and yielding means for normally maintaining the nozzle in a predetermined position but permitting it to move sufficiently to accommodate itself to the work.

6. A nailing die comprising a nail and driver guide mounted to permit transverse movement between limits, and spring means tending to maintain the guide approximately midway between said limits.

7. A nailing die comprising a nail and driver guide mounted for pivotal movement about a point remote from its nozzle end, rigid locating means surrounding said nozzle end and spaced therefrom sufficiently to allow a limited amount of movement thereof, and a spring surrounding the guide and engaging the locating means, said spring tending to center the nozzle end of the guide in the space.

In testimony whereof I have signed my name to this specification.

JOSEPH H. POPE.
